HYDRAULIC SYSTEM FOR DAMPING OR
RETARDING MOVING BODIES

Clinton R. Hanna, Wilkinsburg, Pa., assignor to
Westinghouse Electric & Manufacturing Com-
pany, East Pittsburgh, Pa., a corporation of
Pennsylvania

Application August 25, 1938, Serial No. 226,763

8 Claims. (Cl. 74—5)

My invention relates to a hydraulic control system for damping, or retarding the movement of a movable body and particularly a movable body mounted to oscillate, or to move on both sides of a central or neutral zone.

One object of my invention is to provide a hydraulic control system to retard or damp the movement of a movable body that is pivotally or resiliently mounted in such manner as to be able to oscillate with respect to a central or neutral zone, which may be fixed or which may shift during such movement or oscillation.

An object of my invention is to provide a hydraulic control system in which a valve combination is provided that will establish a reaction pressure function proportional to the volumetric velocity of the displaced medium.

An object of my invention is to provide a two-way hydraulic control system for damping the movement of a movable member that is mounted for oscillation on two sides of a neutral zone.

A further object of my invention is to provide a hydraulic damping system for the control of the precession of a gyroscope.

A further object of my invention is to provide a hydraulic control system to damp the precession of a gyroscope, and to automatically center the gyroscope according to the total swing or excursion of the gyroscope.

Another object of my invention is to provide a hydraulic control system, for a gyroscope, in which the damping effect shall be maintained independent of the viscosity of the fluid used in the hydraulic system.

A further object of my invention is to provide a hydraulic control system that shall damp the precession of a gyroscope, and that shall at the same time effect an automatic centering of the gyroscope at an artificial zone, depending upon the progressively varying average excursion or swing of the gyroscope in its precession movements.

Still another object of my invention is to provide a control system, for a gyroscope, that shall damp the precession velocities to keep them below a fixed maximum speed.

Another object of my invention is to provide a hydraulic control system for general applications of retardation, in which a pressure shall be developed proportional to the volumetric velocity of the hydraulic fluid, or medium, by means of a simple and easily constructed valve system.

In controlling the movement of heavy masses that are so mounted as to oscillate, or to swing from one extreme to another across a variable

neutral or center zone, hydraulic control systems have many advantages because a relatively non-compressible fluid such as oil may be used as the control medium, while at the same time serving as a lubricant for the moving mechanism. With the use of oil as a control medium, simple valve structures may be employed of relatively small size to control relatively heavy masses.

In the present case, I have shown a particular application of my hydraulic control system to damp the precession movement of a gyroscope. In order that a gyroscope may be used as a stabilizing device, for example, on a ship or other vehicle or carriage susceptible to rolling motion, the precession movements of the gyroscope should be retarded or braked to provide a reaction pressure by means of which the gyroscope could introduce a stabilizing force to maintain the normal position of the moving body upon which it is mounted.

In order to provide a satisfactory hydraulic system of control for the gyroscope, the system should be able to maintain its impedance characteristics against the precession movements independently of the viscosity of the fluid or medium used in the hydraulic circuit. Such a system to be satisfactory should also provide an automatic centering arrangement for the gyroscope, to establish an artificial center when the excursions or precessional movements of the gyroscope are not equal in angular displacement with respect to the normal center. In such a system it is also desirable that the precessional velocities be kept below a fixed maximum in order to prevent motion of the gyroscope beyond a fixed maximum angle of travel within the time of a half roll period of the ship. The entire angle of precession is thus kept within a range that will permit the gyroscope to restore itself for effective stabilizing control. The maximum speed of precession should be greater than half of the ship's roll period, but the precession should be limited to prevent overrolling beyond a sixty degree angle.

In applying the hydraulic control system of my invention to the damping of the precession movements of a gyroscope, I preferably mount the control valve device on the bearing shaft of the frame or gimbal for the gyroscope wheel in such manner that the precession movement of the gyroscope will turn a vane or blade within a fixed stationary housing to force the hydraulic medium, such as oil, into a retarding circuit controlled by the device. The valve structure of the device is so arranged as to be cumulatively affected, and to change the area of the valve pas-

sage opening with each precessional movement of the gyroscope in one direction. As the gyroscope precesses in the opposite direction, the valve structure is cumulatively restored to change its opening area back to the original or initial quantity. Thus, so long as the precessional movements are substantially equal in their angular displacements, the valve structure will be continually shifted to a position on one side of its neutral position, and then shifted to the other side of its neutral position. In this manner, the position of the control valve assembly will be governed by the progressive differential of the aggregate precessional movements. So long as such precessional movements are equal and opposite, the control valve assembly will remain substantially balanced in its effect. If the precessional movements tend to preponderate, however, in one direction, the valve assembly will be cumulatively affected to establish a new artificial neutral or central zone, within the extremities of the precessional movements under those conditions. When the precessional movements subsequently preponderate in the other direction, as the moving body tends to resume its normal central position, the position of the valve structure is correspondingly modified to shift the artificial neutral back to the actual neutral or central zone.

While the valve structure shifts position to establish an artificial neutral or central zone, it also modifies the damping effect, upon the precessional movements, to increase the damping or retardation effect upon the precessional movements in that direction in which the precessional movements, for the time being, preponderate. In that manner, the control system automatically compensates to increase the retarding effect against further movement of the controlled body in the direction in which its unbalancing motion tends to preponderate.

By employing the valve structures of proper designs and arrangements, the viscosity of the oil may be eliminated as a control factor, so that the operation of the damping system will be independent of oil viscosity. In this system, the valve structures are designed and cooperatively arranged to provide a pressure that is proportional to the volume velocity. Specifically, such pressure is obtained by a spring valve, whose opening area is proportional to pressure, and a thin-walled orifice. A separate spring-controlled valve that is responsive to the oil pressure serves to limit the volume velocity of oil displacement and thereby limits the maximum value of precession.

The construction of a hydraulic control system, as applied to control the precession of a gyroscope, and the manner in which such system is applied to the gyroscope, in accordance with the principles of my invention, are illustrated in the accompanying drawings, in which:

Figure 1 is a schematic view of a gyroscope structure illustrating a mounting of the hydraulic damper for controlling the precession movements;

Fig. 2 is a vertical and longitudinal sectional view of the hydraulic damper structure;

Fig. 3 is a transverse sectional view, of reduced dimension, taken through the vane and pressure chamber of the assembly shown in Fig. 2;

Fig. 4 is an end elevational view taken from the front or left-hand end of the assembly shown in Fig. 2;

Fig. 5 is a plan view of the assembled unit 75

shown in Fig. 4 with portions broken away to illustrate the valve control structure and the passages to the control valve from the pressure compartments;

Fig. 6 is an enlarged longitudinal sectional view of the valve assembly of the arrangement shown in Fig. 2;

Fig. 7 is an enlarged plan view, partly in section, of the valve control assembly of the arrangement shown in Fig. 5;

Figs. 8 and 9 are front elevational views of the one-way clutches that operate the center valve stem, and

Fig. 10 is a graph of the operating curves of the valve units.

As shown in the drawings, a gyroscope 10 is mounted upon a movable body 11 that is to be controlled to maintain a condition of stability. For the purpose of this description, the body 11 will be considered to be a ship.

The gyroscope 10 comprises the usual gyroscope wheel 12 mounted for rotation around a vertical axis between two bearings 13 and 14 in a ring or housing 15. The housing 15 is mounted for rotation about a horizontal axis on trunnions extending into the two bearings 16 and 17. A shaft 18, that is rigidly connected with the housing 15, extends through the bearing 17 and serves to support and to operate a hydraulic control device 20, to control the precession movements of the gyroscope wheel 12 about the axis of the trunnions.

The control device 20 embodies a vane 21 that is splined on the shaft 18. The vane 21 is disposed within a housing 22 in such manner as to divide the space within the housing into two compartments or compression chambers 23 and 24, that are completely filled with a relatively non-compressible hydraulic medium, such as oil. The housing 22 is anchored at its base by a suitable device 25, to prevent rotation of the housing when the vane is moved by precession movements. The shaft 18 is connected to the supporting housing 15 in which the gyroscope wheel is mounted. The precessional movements of the gyroscope wheel 12 will, therefore, turn the frame 15 in its bearings 16 and 17, and will correspondingly turn the shaft 18 within the stationary housing 22. The power vane 21 will, thereupon be rotated and will exert pressure upon the oil in the compartment towards which the power vane 21 is moved by the precession of the gyroscope. The oil will then be forced out of that compartment by that pressure of the vane 21. By establishing a suitable resistance to the movement of that oil, a reaction pressure can be established to damp the movement of the vane 21, and thereby to dampen the precessional movement of the gyroscope. That reaction pressure then acts to stabilize the body 11.

If chamber 23 is the pressure compartment, oil is forced out of it by the moving vane 21, shown in Fig. 3, and is forced into the valve-controlled passages shown more clearly in Figs. 2, 5, 6 and 7. From the pressure compartment 23, the oil is forced into a communicating passage 30 containing a spring-biased pressure-controlled cut-off valve 31. Pressure compartment 24 communicates with a passage 29 containing a similar valve 31.

The passage 30 (see Fig. 7) extends into the body of the valve housing block 32 mounted above the pressure chambers. The inner end of the passage 30 is provided with a smaller diameter than the outer end of the passage, the latter

end being slightly enlarged to provide a tapered shoulder or seat 33 for the valve 31. The outer end of the passage 30 is threaded and is arranged to be closed by a similarly threaded plug 34. The inner end of the plug 34 is slightly reduced in diameter and is provided with a central positioning boss 35 to locate and seat a pressure biasing spring 36 for the valve 31. The spring 36 is initially unstressed so that the area of the valve opening will be proportional to pressure.

The valve 31 is of the sleeve type and consists of a hollow cylindrical member with a shank section 37 of an external diameter to provide a sliding fit with the inner portion of the passage 30. That shank portion of the valve is partially cut out or slotted at the region 38 to provide an opening along the closed end 39 of the cut-out through which the oil may move from the passage 30 into a connecting passage 41 to the control valve. The outer side wall of the valve 31 is slightly enlarged and is provided with an outwardly diverging inclined or tapered surface 40 of the same inclination as the seating surface 33 of the shoulder in the passage 30 so that the valve may provide a good fit. The head end of the valve 31 is provided with a central seating boss 42 of a shape and diameter corresponding to the seating boss 35 on the closing plug 34, and cooperates with that seating boss 35 to maintain the pressure spring 36 properly seated in operative position between the plug and the valve. A small by-pass leak orifice 31a is provided in valve 31, at the front of its central passage, for a purpose to be referred to later.

The cut-out slot 38 in the valve cylinder, and the end wall 39 of the cut-out slot are so positioned that the end wall 39 will be disposed within the passage 30 and below the transverse plane of the smallest diameter of the tapered seat 33 against which the valve 31 rests in its closed position when the valve 31 is fully closed.

When the oil pressure overcomes the pressure of the valve closing spring 36, the spring 36 is compressed by the movement of the valve 31 and the slot 38 is moved to a position at which the oil may move the transfer passage 41 to a centering control valve generally indicated at 45.

The centering valve 45 is illustrated in Fig. 5 and somewhat more in detail in Fig. 7. It comprises mainly a central valve sleeve or inner cylinder 46 and an encircling sleeve or outer cylinder 47. The outer sleeve 47 is provided with a group of openings 51 angularly disposed around the circumference and extending through the wall of the cylinder 47 at a zone where the openings 51 will communicate with the transfer passage 41 when the outer cylinder 47 is in its operating position.

The outer cylinder 47 is also provided with a similar group of angularly spaced openings 52 around its periphery and extending through its wall in a region axially displaced from the openings 51, so that the openings 52 may communicate with a second transfer passage 53, that is associated with the other pressure compartment 24, through passage 29, which will be referred to later. The space or distance between the openings 51 and 52 is, of course, closed by the wall section 50 in the outer cylinder 47 of 70 the centering valve. That wall section 50 is specifically referred to since the axial dimension along that wall represents a control dimension in the operation and function of the centering valve 45.

5 Beyond the openings 52 the outer cylinder 47 embodies a portion 54 having a smaller internal diameter, and it is internally threaded to receive a correspondingly threaded end portion 55 of the inner control sleeve valve 46. Beyond the threaded portion the outer sleeve 47 embodies an extension 56 that serves as a guide and seat and also as a stop element for a pressure responsive valve 57 that will be referred to and described in detail later.

15 Returning again to the outer sleeve 47 of the centering valve, it will be observed, as shown in Figs. 6 and 7, that the front portion of the outer sleeve 47 is provided with an enlarged section 58 externally threaded to fit into a threaded section 59 in the valve housing block 32. The outer end of the outer sleeve 47 is provided with an annular flange 60 which seats against an oil seal lock washer 61. The outer sleeve 47 is also provided with a series of openings 62 in the shank or body of the sleeve 47, where the openings will communicate with the space 59 between the enlarged threaded section 58 and the valve block, in order to prevent high pressure at the gaskets and packing and also to provide access for lubrication for the inner valve sleeve 46 where it engages the inner wall of the outer valve sleeve 47. The end of the outer sleeve 47 is also provided with an internal thread 64 of slightly larger diameter than the internal sleeve 46, in order to receive an oil seal washer 65 and a locking and positioning plug 66 for the oil retaining washer 65.

35 As shown in Fig. 6, the inner end of the internal sleeve 46 is hollow to provide a tubular section, and the outer end is solid. The inner end is provided with one pair of peripheral slots 71 of substantially rectangular shape with the center lines of the slots 71 in alignment with and 40 in the plane of the inner or rear end edges of the openings 51 of the outer cylinder 47. A similar pair of slots 72 is provided in the internal sleeve 46 that is similarly located with respect to the plane of the forward edge surfaces of the openings 52 in the outer sleeve 47. The relationship 45 between the openings 51 and 71, and between the openings 52 and 72, is such that when the internal sleeve 46 is in its normal neutral position, the openings 71 and 72 will provide passages of correspondingly equal areas to the transfer passages 41 and 53, to permit oil to be transferred from the transfer passages into the central opening of the cylinder section of the internal sleeve 46.

55 When the sleeve 46 is axially shifted, however, the effective openings of the slots 71 and 72 with respect to their associated transfer passages 41 and 53 will be changed. As the effective area of the opening 71 is increased, the effective area of the opening 72 will be decreased, and vice versa.

60 By means of such arrangement, the internal valve sleeve 46 cooperates with the external sleeve 47 to provide a balancing or centering function in controlling the passage of oil from the two pressure compartments 23 and 24 into the internal valve sleeve 46.

65 The manner in which the internal valve sleeve 46 is axially shifted to control the effective areas of the openings 71 and 72 will now be considered. The stem or forward portion of the body of the valve sleeve 46 is shown solid, and it embodies a part 73 that extends outwardly through the oil ring retaining plug 66. Such outer part or extension 73 serves as a means by which the in-

ternal sleeve 46 may be actuated to shift the openings 71 and 72 relative to the openings 51 and 52.

If the body upon which the gyroscope is mounted is subjected to a series of external forces that preponderate in one direction for an interval of time, the gyroscope will be caused to precess correspondingly to a preponderately greater extent in one direction. As a result, the precessing movements of the gyroscope will not be symmetrical with respect to the normal or actual central or neutral axis. In order that the precessing movements of the gyroscope may be made symmetrical and equi-angular with respect to the neutral axis, it becomes necessary to shift such neutral axis and to establish it as an arbitrary or artificial axis, where, and about which, the precessing movements of the gyroscope will be equally and symmetrically distributed.

It is also desirable, in addition to artificially centering the neutral axis of the gyroscope during its precessional movements, to provide a compensating factor for the preponderating external force that is unbalancing the supporting member for the gyroscope and causing the gyroscope to precess. That is, the resistance to the external force, as measured by the precession, should be greater where that force tends to cause preponderant precession. I utilize the centering valve for that purpose by restricting the effective sizes of the valve openings or slots 71 or 72 in internal sleeve 46, to such an extent as may be necessary, in order to provide greater impedance to the precessional movement of the gyroscope in the preponderating direction with respect to its actual normal axis of rotation. In that manner the gyroscope tends to establish a greater restoring force in opposition to the preponderant unbalancing forces that are impressed upon the device to which the gyroscope is applied. Conversely, the other slot of the valve sleeve, that is, either 72 or 71, as the case may be, is correspondingly shifted to provide an effective enlargement of the effective opening between the corresponding transfer passage and the inside passage of the internal valve stem 46, to reduce the impedance to precession movement in the restoring direction towards true balance. It will be understood that impedance is increased for the direction having excess motion and vice versa.

To control the movement of the inner valve sleeve 46 in either direction, two uni-directional clutch devices 74 and 75 are employed. The one-way clutch 74 operates to rotate the inner valve stem or sleeve 46 counter-clockwise as viewed in Figs. 4 and 8, and the other one-way clutch 75 operates to rotate the inner stem or sleeve 46 in a clockwise direction, as shown in Figs. 4 and 9.

The operation of the respective uni-directional clutches 74 and 75 is controlled according to the direction and extent of movement of the power vane 21. The shaft 18 which supports the power vane 21 also supports an end plate 76 upon which are mounted two actuating pins 77 and 78, located to be equi-distantly disposed from a normal vertical center line passing through the center of the shaft 18 and the center of the valve sleeve 46. As shown in the side view in Figs. 2 and 6, the actuating pin 78 extends outwardly further than the pin 77, and upwardly as an L-shaped element to reach its clutch device, which is axially displaced on the external extension or actuating section 73 of the internal sleeve 46.

The uni-directional clutch 74 comprises, briefly, an annular ring or actuator 80 provided with two integral depending operating arms 81 and 82 as a fork, a clutch roller 83, a back arm 84 on the actuator, and an overcenter spring 85, that is pivotally connected at one end to the back arm 84 of the actuator, and that is pivotally anchored at its other end to a stationary pin 86. A stationary stop 87 limits the motion of the clutch actuator 80 and, therefore, of the clutch, in one direction, and a stationary stop 88 similarly limits the motion of the clutch in the opposite direction. Spring 89 biases the clutch roller 83 to engaging position between the actuator of the clutch 74 and the actuating extended portion 73 of the internal sleeve 46, to prevent any lost motion in the actuating operation.

The clutch 75 is provided with similar elements designated by the same numerals primed, except that it is mounted with the roller 83' disposed to engage a surface that is oppositely inclined to the surface 90', so that it will disengage when the clutch 74 engages and will engage when the clutch 74 disengages.

The purpose of the overcenter springs 85 and 85' on each clutch is to compel each clutch to move to its extreme position in either direction of actuation, in order that the fork arm such as 81 or 82, by means of which the clutch has been actuated to one position or the other, shall be moved out of the way of the actuating pin 77 or 78 of the clutch, upon the return movement of that pin, when the power vane 21 returns to its neutral position in response to the return of the gyroscope towards its neutral position.

So long as the precessional movements of the gyroscope are equal from its normal neutral center line, each clutch motion that causes a corresponding movement or turn of the central sleeve 46 will be counter-balanced and counteracted by a corresponding movement effected by the other clutch, to restore the sleeve to its initial position. Consequently, so long as the precessional movements of the gyroscope are symmetrical, the valve movements will be symmetrical and will establish or maintain an average zero movement with respect to the normal neutral position of the centering valve 46.

When the external motion-controlling forces preponderate in one direction against the member or device upon which the gyroscope is supported or mounted, the gyroscope will correspondingly precess to a greater degree angularly in one direction than in the other. As the low side swing becomes less, it will tend to reach a value at which there would be no restoration of the internal sleeve valve 46. Consequently, the continued precessional movements in the preponderating direction of movement with respect to the normal center will cause continued actuation of the internal sleeve valve 46, by such movements in the preponderating direction, without any corresponding restoration or return movements of the internal valve sleeve 46. As a result, the internal sleeve 46 will be shifted to a position that will represent and temporarily establish a new artificial center line or neutral zone about which the angular movements of the power vane 21 will be equal. Thus the precessional movements of the gyroscope will be artificially equalized with respect to the temporary artificial neutral zone or center line for the gyroscope.

While the internal valve sleeve 46 is in such off-normal position, in accordance with the new artificial center line, the valve openings 71 and 72

will be shifted with respect to their normal center-line positions, and one of the openings, either 71 or 72 depending upon the direction of the preponderance, will be shifted to introduce a constricting effect by reason of the reduced dimension in the area of the opening presented to the passing oil.

After the oil enters the inner valve cylinder or sleeve 46 through the openings 71 or 72, it proceeds out of the valve cylinder 46 into a chamber or compartment 95, and thence into the cylindrical spring controlled valve 57 through an opening 96 in the end wall 97 of the valve cylinder 57. The valve cylinder 57 is provided with an external annular flange 98 which serves as a stop element to control the limit of opening movement of the valve cylinder 57 in response to the biasing action of its control spring 99. The cylinder 57 may move in the opposite direction to full closed position, as controlled by the position of a stop surface 104 against which the flange 98 may contact when the valve cylinder 57 is forced against the biasing spring 99 by the increased oil pressure when the oil enters the compartment 95 prior to passing through the opening 96 in the end wall of valve cylinder 57. As shown in the drawings in Fig. 7, a compartment 102 is formed in the valve block to provide space for the valve cylinder 57 when it is actuated in that direction by the increased oil pressure.

As the oil is circulated through the valve 57, the difference between the pressures on the opposite sides of the end wall 97, at the entering orifice 90, due to the square law drop of pressure as fluid flows through the orifice, acts upon the valve 57 against the biasing spring 99. When the velocity through the orifice 96 exceeds a predetermined value, the valve 57 will be moved by such pressure differential to reduce the effective area of the outlet orifice 104. The velocity of the oil through valve 57 will thus be diminished to the permitted value.

The valve cylinder 57 is also provided with a slot 103 that communicates with the opening 104 in the valve block to permit the oil to pass out of the cylinder valve 57 and through the opening 104 into a discharge conduit 105 that leads to a cooling system for the oil. A conduit 106 returns the cooled oil from the cooling system and supplies it through two conduit connections 107 and 108 to the pressure compartments 23 and 24, respectively, through two self-seating, self-closing pressure valves 109 and 110, respectively. A by-pass conduit connection 112 connects the conduit 105, leading to the cooling system, and the conduit 106 from the cooling system, and serves to by-pass a predetermined portion of the circulated oil so that only a desired percentage will be cooled, all of which is predetermined (or may be adjustably controlled), by the relationship between an opening 115 in the conduit 105 and an opening 116 in the by-pass conduit 112.

I have illustrated, in Fig. 6, a passage 117 in the valve block, proceeding from the opening 104 leading to the cooling system conduit 105 and proceeding to a passage 118, to serve the contact surface between the top of the power vane 21 and the cover plate 120. The lubricating passage 118 also communicates with the opening 62 in the external sleeve 47, adjacent the chamber 59 in the valve block in order to provide lubrication for the outer surface of the inner valve sleeve 46 where it engages the surface of the stationary sleeve 47. The lubricating passage 118 also communicates with an orifice 121 through

which lubrication is supplied to the contacting surface 122 where the rotating shaft 18 engages a section of the valve block. An oil retaining washer 123 is provided along the side orifice 121 and the washer is held in place by a threaded lock ring 124 that is threaded onto a portion 125 of the block.

By means of the various lubricating passages indicated and referred to, all normally frictionally engaging surfaces are lubricated.

The action of the spring valve 31 is such that its opening area is proportional to the pressure of the oil flowing through. The pressure P may be evaluated thus,

$$P = \frac{1}{2}(dv^2)$$

where d is the density of the oil, and v is the linear velocity of the oil. The linear velocity, v , may be written

$$v = \frac{V}{A}$$

where V is the volumetric velocity and A is the area of the opening of valve 31. Thus,

$$P = \frac{1}{2}dv^2 = \frac{1}{2}d\left(\frac{V}{A}\right)^2$$

and since

$$P \propto A, P \propto \frac{dV^2}{2D^2}, \text{ or } P \propto V^2$$

The curve for that relation

$$P \propto V^2$$

may be represented by curve A in Fig. 10. By adding the thin walled orifice of the centering control valve 45 in series with the spring valve 31, the additional relation between pressure and volumetric velocity may be established as shown by curve B in Fig. 10. The two curves A and B add up to form curve C which shows a direct proportionality between the oil pressure and the volumetric velocity up to point D. Beyond that point D on the curve, the volumetric velocity is maintained limited to that value, as shown by vertical curve E, irrespective of increase in the pressure. Such control is provided by the volume velocity limiting valve 57, which controls the velocity by regulating the size of the orifice between slot 103 and opening 104. The small hump C—a at the lower end of curve C is eliminated in the control system by the small by-pass leak at 31—a in valve 31, to reduce the developed pressure to the direct-proportionality shown by line F.

Thus, by the combination of valves having proper correlated functional characteristics the system is controlled to establish a proportional relation between the oil pressure and the volumetric velocity of the displaced oil; and to establish a definite maximum volumetric velocity and, therefore, a maximum procession velocity.

Moreover, by controlling the area of the series orifice in valve 45, automatic centering of the gyroscope is established by setting up an artificial temporary center, while the external forces acting against the ship, for example, are not equalized, and the gyroscope tends to precess more in one direction than in the other from its actual neutral or central position.

In order to procure such artificial centering, the inner sleeve valve element 46 is rotated slightly by the uni-directional clutch or ratchet devices 74 and 75 whenever a certain angle of precession is exceeded, for example, whenever the

angle of 35 degrees from vertical is exceeded. If the deflection should be, for example, 40 degrees or more, the clutches will not rotate the inner sleeve valve element 46 on returning to center but will remain cocked and held in position by the toggles, awaiting the next stroke.

If the precession exceeds the 35 degrees movement to one side of center more frequently than to the other side, the unbalance will be adjusted for in small steps by the clutches until the artificial center is reached, at which the number of times the 35 degree position is reached will be the same for both sides.

The invention is not necessarily limited to a particular kind of valves, or to the details of construction, or to the arrangement shown, since all of those things may be varied without departing from the spirit and scope of the invention as set forth in the appended claims.

I claim as my invention:

1. The combination with a gyroscope and a mounting support to permit precession movements of hydraulic means including a substantially non-compressible liquid for damping such precession movements, and means for automatically controlling said damping means to establish centering of the gyroscope with respect to the full range of excursion.

2. The combination with a gyroscope and a mounting support to permit precession movements, of hydraulic means including a substantially non-compressible liquid for damping such precession movements to keep the precessional velocities below a fixed maximum, and means responsive to the angle of precession for controlling the damping function of the hydraulic means.

3. The combination with a gyroscope and a mounting support to permit precession movements, of hydraulic means including a substantially non-compressible liquid for damping such precession movements, and means responsive to unbalanced angles of precession for establishing correspondingly asymmetric damping.

4. The combination with a gyroscope and a mounting support to permit precession movements, of means for damping such precession movements, and means responsive to a progres-

sive average of precession excursions for controlling the symmetry of the damping function.

5. The combination with a gyroscope rotor, mounted for rotation around a vertical axis, of a gimbal therefor provided with trunnions to permit rotation about a horizontal axis, an extension on one trunnion, and hydraulic damping means controlled by said extension, said means including an oscillatable vane moved by the trunnion, a housing for the vane and arranged to provide two pressure chambers, a liquid medium in the pressure chambers to resist movement of the vane, and outlet valves connected to the chambers to control the expulsion of the liquid under the pressure developed by the vane.

10 6. The combination with a gyroscope and a mounting support to permit precession movements, of hydraulic means including a substantially non-compressible liquid for damping such precession movements, and means for centering the gyroscope with respect to its total excursion, said means including a double entrance valve communicating with the hydraulic means, and unidirectional clutch means for selectively controlling the valve to position the valve centrally with respect to the total excursion of the gyroscope.

20 7. The combination with a gyroscope and a mounting support to permit precession movements, of hydraulic means including a substantially non-compressible liquid for damping such precession movements, including means responsive to the precession movements in each direction for damping the movements of precession, and means responsive to the respective precessional excursions for controlling the damping impedance of the hydraulic means.

30 8. The combination with a gyroscope and a mounting support to permit precession movements, of hydraulic means for damping such precession movements including a liquid medium, including valve means having two entrance ports, and means responsive to precession movements for forcing the liquid through said ports, and means for unbalancing the areas of said ports in accordance with an unbalance of precession movements.

CLINTON R. HANNA.
